(57) **CLAIM**

The ornamental design for a display device component, as shown and described.

DESCRIPTION

FIG. 1 is a front perspective view of a display device component showing our new design;

FIG. 2 is a front elevation view of the display device component of FIG. 1;

FIG. 3 is a back elevation view of the display device component of FIG. 1;

FIG. 4 is a right elevation view of the display device component of FIG. 1;

FIG. 5 is a left elevation view of the display device component of FIG. 1;

FIG. 6 is a top elevation view of the display device component of FIG. 1;

FIG. 7 is a bottom elevation view of the display device component of FIG. 1; and,

FIG. 8 is a rear perspective view of the display device component of FIG. 1.

Broken lines are environmental only and form no part of the claimed design.
